UNITED STATES PATENT OFFICE.

NAPOLEON B. PIERSALL, OF NEWARK, NEW JERSEY.

FASTENER.

Application filed May 3, 1923. Serial No. 636,506.

To all whom it may concern:

Be it known that I, NAPOLEON B. PIERSALL, a citizen of the United States, and a resident of Newark, in the county of Essex and State of New Jersey, have invented a new and Improved Fastener, of which the following is a full, clear, and exact description.

This invention is an improvement in latch fasteners for miscellaneous uses and of the kind disclosed in U. S. Letters Patent No. 997,832, issued to one Klein and myself, in that the present latch, like the one there disclosed, is not a type of latch which must be destroyed to be disengaged like a familiar form of car-seal, and in that the present latch comprises essentially two structures one of which has a pocket normally open at the front and incorporating a detent spring 10 for the head of the other structure and overhanging the entrance to the pocket, the pocket otherwise having walls girthed or substantially girthed the pocket in rear of such opening, and the other structure having a head as just mentioned constructed to lift the spring in passing into the pocket and further having a portion for being detained by the spring on full insertion of the head endwise into the pocket, to the end 20 that unlike some similar constructions of the devices of others constituting prior art relative to said patent and relative to the invention of this application, the two structures, once engaged, may not be disengaged 30 except on a deliberate rocking of the spring element of the pocket-carrying structure relative to the head-carrying structure and a rocking of the spring element across the plane of the line of endwise advance of the head into the pocket in coupling up the structures.

The feature of the construction of said Klein and Piersall patent was, however, an arrangement whereby a multi-part construction and one rather complicated and expensive had to be provided, chiefly because such overhanging spring of the pocket and hence the whole pocket-carrying structure could not practically be made out of a single unitary piece of sheet metal. Such difficulty was the result of a conception of the pocket as a recess cut out of a solid piece of material, and therefore the spring element was necessarily a separate piece having an opening and hence the spring was really a frame-like device presenting an

inner edge beyond the pocket mouth and below the pocket top and facing the interior of the pocket and consequently a detent edge of the spring element not constituting a 60 terminal or even an exterior bounding edge thereof.

According to the present invention, the pocket is preferably incompletely girthed near its mouth and has side portions and 65 part of the top portions of its walls formed of upwardly bent or curled tabs offset from opposite sides of a unitary piece of sheet material, while the spring device is a considerably longer tab or rearward extension 70 of said piece and reversely bent to lie above the entire length of the pocket, thus to permit the free end of the spring to be again bent, preferably by a reverse bend, to provide the spring-detent means proper at a terminal edge thereof facing the pocket mouth. 75

According to the present invention, further, the head member is likewise preferably of unitary sheet metal construction, thus satisfying another important object of 80 the invention, which is to provide a latch of the kind above indicated wherein each of the two separable structures is adapted to be constructed out of a sheet metal blank and with a minimum of waste material and 85 a minimum of die expense and upkeep.

The invention will be best understood from a consideration of the following detailed description when taken in connection with the accompanying drawing forming 90 part of this specification; with the understanding, however, that such drawing illustrates, merely by way of example, one possible embodiment of the invention, and that the invention is not confined to any strict 95 conformity with the showing in the drawing, but may be changed and modified so long as such changes and modifications mark no material departure from the salient features of the invention as expressed in the 100 appended claims.

For instance, in said drawing, Figs. 1 to 3 show an embodiment of the new latch exhibiting all the advantages above stated when used as a quick detachable yet secure lock for holding down the hood sections for an automobile, and Figs. 4 to 7 show the embodiment for use as a garment, tent-flap or other textile-applied fastener also according to the present invention, but a type 105 of fastener which will generally be produced from very light sheet material and 110

according to very much diminished dimensions as compared with the latch of Figs. 1 to 3.

More in detail:

Fig. 1 is a perspective view of such an automobile latch;

Fig. 2 is a central vertical section of the latch of Fig. 1, but showing the parts on a slightly larger scale;

Fig. 3 is a transverse section taken on line 3—3 of Fig. 2;

Fig. 4 is a side elevation of the pocket member, detached, of a latch for garments or the like;

Fig. 5 is a top plan view of the member of Fig. 4;

Fig. 6 is a view similar to Fig. 4, but showing the complementary head member, detached; and

Fig. 7 is a top plan view of the member of Fig. 6.

It will be appreciated that the latch of Figs. 4 to 7, if the latch of Figs. 1 to 3 is assumed to be shown on about or slightly larger than the actual-size scale, is shown, for purposes of clarity, on a very much larger scale than that which will actually be employed.

Believing that the structural details of the latch of Figs. 1 to 3 will be better understood if such details of the simpler latch of the other views are first described, reference will preliminarily be made to Figs. 4 to 7.

Here it will be seen at a glance that the head as well as the pocket member is formed of a single piece of sheet material, as spring steel, brass or the like; and that each carries, in addition to its tab-like portions 8 and 8', having apertures 9 and 9' by which the members may be attached, by stitching or otherwise, to the parts carrying them, a pair of tabs at opposite sides of the member and bent or curled up toward each other to form a more or less resilient claw or yoke-like structure above the bottom plane of the member.

In the case of the head-carrying member 10 of Figs. 6 and 7, these side tabs, marked 11, form a hollow head, hereinafter called the head 11. This head is split lengthwise of its top, as at 12, and may be said to taper in vertical longitudinal section as well as in horizontal longitudinal section. In the case of the pocket-carrying member 14 of Figs. 4 and 5, these side tabs, marked 15, form a pocket structure, hereinafter called the pocket structure 15, somewhat similar to the hollow head of the head-carrying structure. That is to say, such pocket, really a split band clasp according to the present invention, is yet tapered so as to have its internal surface snugly to embrace the outside surface of the head of member 10 when inserted to the maximum in the pocket, and the pocket has a top longitudinal split estab-

lished by the spaced relation of the mutually approaching free edges 16 of the side curled tabs. This split is of dissimilar shape to that of the split 12 of the head-carrying member, and is designed for overlying roof portions of the head on opposite sides of the split of the latter.

The edges 16 of the side-curled tabs establishing the pocket 15 are prolonged as shown best in Fig. 5 to establish a pair of small leaves 17, for a purpose which will appear in a moment.

Pocket-carrying member 14 further carries, but as its sole additional element to those just described, a long tab or floor-portion extension 18 presenting the spring-detent, hereinafter referred to as the spring 18, or the manually releasable automatic head-latching element 18. As will be seen, this long tab, springing out from the rear end of the floor-portion of member 14, is bent or curled up and then bent further to extend over the entire length of pocket 15 to a point some distance beyond the forward ends of leaves 17. Also, the forward terminal portion 19 of the spring is bent down and back toward the pocket to present a rearwardly directed edge facing the pocket mouth and below said leaves 17. These parts 17 and 19 thus co-act to limit the extent of temporary upward movement of the head latching element or spring 18, to permit the head to be instantaneously slipped clear of the pocket, when a finger-nail or the like is inserted under and pulled upward relative to portion 19 of spring 18.

Referring now to Figs. 1 to 3, we find again a unitary pocket and spring-detent member, and a unitary head member; the former member to be fixedly carried by the movable hood section A and the latter to be fixedly carried by a shelf structure B on the automobile body, as a fender portion.

The pocket member, marked 14^a, carries a handle or operating projection 21, offset from spring-detent 18', for manually releasing the latter; which handle may have its handle-shank 21^a also formed of integral tabs if desired, but which tab construction is not the one affording most economical manufacture, in view of probable material waste, as will be understood. In all other respects, the pocket member is precisely similar to the pocket member of Figs. 4 and 5, except of course that there is no necessity for having the terminal portion 19' of element 18 quite as long as the similar portion 19 of Fig. 4.

In the case of the head member of Figs. 1, 2 and 3, there marked 10^a, the same is rather similar to the head member of Figs. 6 and 7; indeed, the only difference is that the floor portion of the member is not uniplanar, as in Fig. 6, but is provided with a central upstanding tapering rib 22 of tri-

angular cross-section. This rib is provided for purposes of imparting increased rigidity to the entire head member and conveniently providing attaching tabs 8^b, oppositely and symmetrically arranged relative to rim 22 as shown, and extending in a plane perpendicular to the attaching tabs 8^a of pocket member 14^a, said plane being also perpendicular to the line of extension of the 10 head member.

The slight resiliency of the hollow type of construction provided by the present invention for the head of one member and for the pocket of the other is particularly important 15 in the case of the embodiment last described, as will be understood. Such a construction allows for slight relative shifting of different portions of the unitary pieces of which the two members are made, to take 20 care of a slight swinging movement of a section A in coupling up the two members.

I claim:

1. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head 25 in the pocket, and of the type further including a detent spring carried by the pocket-carrying structure for automatically snapping into engagement with a part of the head-carrying structure when the latter structure has its head entered in the pocket to said predetermined extent and so as to permit manual release of said head from the spring on relatively and momentarily throwing the spring to an abnormal position, a pocket member formed of a unitary piece of sheet material and carrying a pocket 30 having an open mouth, and a detent spring having a length overlying the top of the pocket and having a terminal portion 35 downwardly bent to extend below the top of the pocket.

2. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head 40 in the pocket, and of the type further including a detent spring carried by the pocket-carrying structure for automatically snapping into engagement with a part of the head-carrying structure when the latter structure has its head entered in the pocket to said predetermined extent and so as to permit manual release of said head from the spring on relatively and momentarily throwing the spring to an abnormal position, a pocket member formed of a unitary piece of sheet material and carrying a pair of tabs 45

on opposite sides bent up and toward each other to form a resiliently established pocket of gradually decreasing cross-section along the length of the member and having an open mouth at its larger end. 70

3. In a releasable, repeatedly usable latch of the type including a pocket-carrying structure and a head-carrying structure, wherein pocket and head are so designed as to preclude introduction of the head into 75 the pocket beyond a predetermined extent and to preclude lateral rocking of the head in the pocket, and of the type further including a detent spring carried by the pocket-carrying structure for automatically snapping into engagement with a part of the head-carrying structure when the latter structure has its head entered in the pocket to said predetermined extent and so as to permit manual release of said head from 80 the spring on relatively and momentarily throwing the spring to an abnormal position, a head member and a pocket member 85 each formed of a unitary piece of sheet material and each carrying a pair of tabs on opposite sides bent up and toward each other to form a pocket open-mouthed at one end, one of said pockets having an exterior substantially conforming to the interior of the other. 90

4. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head in 95 the pocket, and of the type further including a detent spring carried by the pocket-carrying structure for automatically snapping into engagement with a part of the head-carrying structure when the latter structure has its head entered in the pocket to said predetermined extent and so as to permit manual release of said head from the spring on relatively and momentarily throwing 100 the spring to an abnormal position, a head member formed of a unitary piece of sheet material and carrying a pair of tabs at opposite sides bent up and toward each other to form a resiliently established pocket of gradually decreasing cross-section along the length of the member and having an open mouth at its larger end. 105

5. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head in 110 the pocket, and of the type further including a detent spring carried by the pocket-carrying structure for automatically snapping into engagement with a part of the head-carrying structure when the latter structure has its head entered in the pocket to said predetermined extent and so as to permit manual release of said head from the spring on relatively and momentarily throwing the spring to an abnormal position, a head member formed of a unitary piece of sheet material and carrying a pair of tabs at opposite sides bent up and toward each other to form a resiliently established pocket of gradually decreasing cross-section along the length of the member and having an open mouth at its larger end. 115

6. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head in the pocket, and of the type further including a detent spring carried by the pocket-carrying structure for automatically snapping into engagement with a part of 120 the head-carrying structure when the latter structure has its head entered in the pocket to said predetermined extent and so as to permit manual release of said head from the spring on relatively and momentarily throwing the spring to an abnormal position, a head member formed of a unitary piece of sheet material and carrying a pair of tabs at opposite sides bent up and toward each other to form a resiliently established pocket of gradually decreasing cross-section along the length of the member and having an open mouth at its larger end. 125

7. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head in the pocket, and of the type further including a detent spring carried by the pocket-carrying structure for automatically snapping into engagement with a part of 130 the head-carrying structure when the latter structure has its head entered in the pocket to said predetermined extent and so as to permit manual release of said head from the spring on relatively and momentarily throwing the spring to an abnormal position, a head member formed of a unitary piece of sheet material and carrying a pair of tabs at opposite sides bent up and toward each other to form a resiliently established pocket of gradually decreasing cross-section along the length of the member and having an open mouth at its larger end. 135

the head-carrying structure when the latter structure has its head entered in the pocket to said predetermined extent and so as to permit manual release of said head from the spring on relatively and momentarily throwing the spring to an abnormal position, a pocket member formed of a unitary piece of sheet material and carrying a pocket having an open mouth, and a detent spring having a length overlying the top of the pocket and having a terminal portion downwardly bent to extend below the top of the pocket, said pocket member also having a longer tab located between the two tabs first mentioned and bent up to overlie said two tabs and having a terminal portion downwardly bent to extend below the top of the pocket.

6. In a releasable, repeatedly usable latch of the type including a pocket-carrying structure and a head-carrying structure, wherein pocket and head are so designed as to preclude introduction of the head into the pocket beyond a predetermined extent and to preclude lateral rocking of the head in the pocket, and of the type further including a detent spring carried by the pocket-carrying structure for automatically snapping into engagement with a part of the head-carrying structure when the latter structure has its head entered in the pocket to said predetermined extent and so as to permit manual release of said head from the spring on relatively and momentarily throwing the spring to an abnormal position, a pocket member formed of a unitary piece of sheet material and carrying a pocket having an open mouth, and a detent spring having a length overlying the top of the pocket and having a terminal portion downwardly bent to extend below the top of the pocket, said pocket member having an attaching tab extending in the plane of the bottom of the pocket, there being provided a handle projection on the spring intermediate its ends and substantially midway of its width for throwing the spring to abnormal position as aforesaid, said projection being substantially perpendicular to the plane of said attaching tab.

7. In a releasable, repeatedly usable latch of the type including a pocket-carrying

structure and a head-carrying structure, wherein pocket and head are so designed as to preclude introduction of the head into the pocket beyond a predetermined extent and to preclude lateral rocking of the head in the pocket, and of the type further including a detent spring carried by the pocket-carrying structure for automatically snapping into engagement with a part of the head-carrying structure when the latter structure has its head entered in the pocket to said predetermined extent and so as to permit manual release of said head from the spring on relatively and momentarily throwing the spring to an abnormal position, a head member formed of a unitary piece of sheet material and carrying a pair of tabs at opposite sides bent up and toward each other to form a resiliently established pocket of gradually decreasing cross-section along the length of the member and having an open mouth at its larger end, a portion of the head member between its tabs at opposite sides being formed into a central longitudinal rib of gradually increasing height toward the rear end of the head member, said head member further carrying attaching tabs projecting beyond the rear end of the rib bent oppositely to extend laterally and outwardly beyond the rib.

8. A fastener, comprising a socket member, a stud member fitting the socket member, and a spring locking tongue on the outside of the socket member projecting beyond the socket and engaging the head of the stud.

9. A fastener, comprising a socket member, a stud member fitting the socket member, and a spring locking tongue on the outside of the socket member projecting beyond the socket and engaging the head of the stud, said tongue having a finger grip adjacent its free end.

10. A fastener, comprising a socket member, a stud member fitting the socket member, a spring locking tongue on the outside of the socket member projecting beyond the socket and engaging the head of the stud, and laterally bent finger gripping portions at the edges of the tongue.

NAPOLEON B. PIERSALL.
